ELECTRICAL SPACE DISCHARGE TUBE
LEAD-IN CONSTRUCTIONThomas H. Briggs, Jr., Wellesley Hills, Mass.,
assignor to Raytheon Production Corporation,
Newton, Mass., a corporation of Delaware

Application June 15, 1938, Serial No. 213,784

8 Claims. (Cl. 250—27.5)

The present invention relates to a lead-in construction for an electrical space discharge tube, and more particularly to such tubes which operate with one or more of the electrodes at an elevated 5 temperature.

Electrical space discharge tubes are ordinarily made with a sealed envelope having electrical conductors sealed through a glass wall therein in order to provide electrical connections to the 10 electrodes within the envelope. Heretofore very little attention has been paid to the thermal characteristics of the structure between the electrode itself and the lead-in between said electrode and the wall of the container. I have 15 found, however, that the thermal properties of this lead-in construction play a very important part of the operation and characteristics of the resulting tube structures. For example, in connection with cathodes, particularly of the indirectly-heated type, it has been difficult to maintain the temperature of the coated portion of 20 said cathode substantially uniform throughout without complications in the construction of the cathode itself. Also in connection with relatively massive electrodes having a high heat capacity, difficulty has been encountered in excessive amounts of heat being transferred therefrom to the glass wall from which the lead-in conductor is sealed, thus facilitating electrolysis 25 of the glass at that point.

One of the objects of my invention is to devise a lead-in construction for an electrical space discharge tube which will control the heat distribution in and from the electrode to which it 30 is connected so as to eliminate previous difficulties.

Another object is to devise such a lead-in for a cathode construction so as to produce a uniformity of temperature along the coated portion 35 thereof, whereby a uniform emission from said cathode is produced.

A still further object is to eliminate the possibility of transfer of sufficient heat from a hot electrode of large heat capacity to the glass wall 40 of an envelope to such an extent as to facilitate electrolysis of the glass.

The foregoing and other objects of my invention will be best understood from the following description of exemplifications thereof, reference 45 being had to the accompanying drawing, wherein:

Fig. 1 is a side view of an electrical space discharge tube embodying my invention, one of the electrodes therein being partly broken away to illustrate the underlying construction;

Fig. 2 is an enlarged view of the lead-in con-

struction between the cathode and stem of the types shown in Fig. 1;

Fig. 3 is a perspective view of another tube embodying my invention, the glass envelope of said tube being broken away so as to show the internal construction thereof more clearly;

Fig. 4 is an enlarged view of the lead-in construction from the anodes to the stem of the tube illustrated in Fig. 3; and

Fig. 5 is an enlarged fragmentary cross-section taken transversely through the bottom part of the electrode structure of Fig. 3.

In Figs. 1 and 2 the device shown therein consists of a glass envelope 1 having a reentrant stem 2, at the upper end of which is formed a glass press 3. Upon this press is supported an anode 4, a cathode 5, and a control grid 6 surrounding the cathode 5 and interposed between it and the anode 4. The anode is supported by two anode standards 7—7 sealed into the press 20. The two anode standards 7 carry an upper insulating spacer 8 and a lower insulating spacer 9 rigidly secured to said standards. These spacers form with the standards 7 a relatively rigid construction upon which the electrodes themselves 25 are supported. The anode 4 is directly welded to the lead-in wires 7, while the grid 6 and the cathode 5 are supported from the insulating spacers 8 and 9. An electrical connection is made to the grid 6 by means of a lead-in wire 10 sealed 30 in the press 3 and electrically welded to one of the side rods of said grid.

The cathode 5 consists of a hollow tubular metal member, preferably of nickel, carrying a coating 15 thereon of suitable emitting material, such as for example a mixture of barium and strontium oxide. The cathode is heated so that the coating 15 is raised to temperature of thermionic emission by means of a heater within the hollow tubular cathode member. This heater consists of a filament with the two ends 11—11 40 projecting from one end of the cathode sleeve. Electrical connection is made to the cathode sleeve by means of a lead-in wire 13 sealed in the press 3 and a cathode connector 14 connecting the lead-in wire 13 and the cathode sleeve. The connections between the connector 14 and the cathode 5 and the connector 14 and the lead-in wire 13 are made by having the connector 14 electrically welded to each of said 45 members. Electrical connection is made to the filamentary heater lead 11 by a pair of lead-in conductors 12 likewise sealed in the press 3. The tube is provided with the usual base 16 having a plurality of base prongs 17 to which 50

the outer ends of the various lead-in wires are connected, thus establishing the external electrical connection to the electrodes within the envelope.

5 Heretofore the electrical connector 14 has been made of a material substantially similar to that from which the cathode sleeve 5 is constructed. This material is ordinarily nickel. Previous considerations as to this connector have been simply 10 that it should be a good electrical conductor so as to make a good electrical connection to the cathode sleeve. I have found, however, that if the connector 14 is made of an electrical conductor which has a substantially lower thermal conductivity than that of the material of which the cathode itself is made, the operation of the tube is substantially improved. For example, if the connector 14 is made of an iron-nickel alloy having substantially 36% nickel, 63% iron, and 15 a very small amount of carbon, the thermionic emission and the mutual conductance of the tube are much higher than those in which the pure nickel is used for the connector 14. The alloy to which I have referred is known in the trade as Nilvar, and has a thermal conductivity of approximately one-seventh that of pure nickel. It appears that the improvement in the result which is produced depends upon the lowered thermal conductivity of this alloy. Due to the 20 difference in thermal conductivity along the system which occurs at the point of connection between the connector 14 and the cathode sleeve 5, the entire cathode sleeve can be maintained at a relatively high and uniform temperature, 25 and at the same time a sharp drop in temperature can occur at said connection. Of course other electrical conductors having a substantially lower order of thermal conductivity than nickel could likewise be used. For example, other nickel-iron alloys having varying amounts of nickel and iron could be used. One alloy in particular, 30 namely that having 42% nickel and about 58% iron, has been found to be particularly useful in this connection. Such an alloy welds very readily to nickel conductors, and otherwise produces the beneficial results mentioned above. Also nickel silicon alloys consisting of nickel with a relatively small percentage of silicon therein likewise possess the requisite low thermal conductivity and good electrical conductivity to produce 35 the novel results which are inherent in my invention. In these alloys the silicon content may be of the order of 3% to 5% silicon, although higher silicon content may be used. It appears 40 that the addition of the silicon to the nickel in this alloy lowers the thermal conductivity to the requisite degree without interfering too greatly with the electrical conductivity or with the ability of this alloy to be welded to nickel electrodes and 45 nickel conductors.

60 Although I have described my invention as being applied to a connector for an indirectly heated cathode, I have also found that connectors of this kind can be used for other electrodes, 65 such as, for example, an anode in certain cases with very beneficial results. An arrangement of this kind is shown in Figs. 3, 4 and 5 which illustrate a double anode rectifier tube. This tube is made with a glass envelope 18, which 70 in Fig. 3 is shown broken away so that the structure within said envelope can more readily be seen. The envelope 18 is provided with a re-entrant stem 19 having a glass press 20 at the upper end thereof. This press 20 supports a pair 75 of anodes 21 within each of which is supported

a filamentary thermionic cathode 22. The electrode assembly is supported primarily from a pair of supporting standards 23 sealed in the stem 18. The standards 23 support an upper insulating spacer 24 and a lower insulating spacer 25. 5 Each anode 21 is provided with a flange 26 each of which is connected to an anode standard 27 and likewise is received between the upper and lower insulating spacers 24 and 25, whereby the anodes 21 are supported in position. The anode standards 27 project through the spacers 24 and 25. To the lower end of each anode standard 27 is electrically welded an anode connector 28, which in turn is connected to an anode lead-in conductor 29 sealed in the press 20. 10 15

In order to support the filamentary cathodes 22, the upper insulating spacer 24 supports a pair of posts 30 to each of which is welded a resilient hook 31 which supports the upper end of the associated filamentary cathode 22. The lower insulating spacer 25 has supported thereon a pair of posts 22 to which is welded an intermediate connector 33. The opposite ends of this intermediate connector 33 are welded respectively to an end of each of the filamentary cathodes 22. The other end of each cathode 22 is connected to a conductor 34 which in turn is welded to an adjacent standard 23. These standards 23 therefore serve as the lead-in conductors for the two filamentary cathodes 22 connected in series. 20 25 30

The tube is provided with the usual base 35 having a plurality of contact pins 36 to which the lead-in conductors are connected, and in this way an external electrical connection is made 35 to the electrodes.

The connectors 28 in the arrangement shown in Figs. 3, 4 and 5 are made of the same material as that described in connection with the connector 14 in Figs. 1 and 2. The anodes 21 during 40 operation are raised to a relatively high temperature, due to the passage of an electrical discharge in the tube and also due to heat radiated from the filamentary cathodes 22. The anodes 21 are relatively massive, and therefore possess 45 a considerably high heat capacity. Heretofore difficulty has been encountered in excessive amounts of heat travelling from the anodes through the connectors 28 to the press 20. This excessive amount of heat has raised the temperature of the press 20 to a point at which the glass becomes partially conductive. Under these conditions the voltages impressed upon the lead-in wires have caused electrolysis of the glass which has produced a premature failure of the 50 tube, due to air leaks along the wires where the glass has been electrolyzed. In a device made in accordance with my invention, the anodes 21 and the standards 27 are usually made of nickel, while the connectors 28 are made of a special 55 material having a considerably lower order of magnitude of thermal conductivity. Under these conditions a large temperature gradient can exist between the standards 27 and the lead-in conductors 29 without an excessive amount of heat 60 flowing through the connectors 28. Under these conditions the stem 20 remains cool and electrolysis does not occur. Such an arrangement makes for a greater utilization of the tube structure inasmuch as larger discharge currents can 65 be carried, thereby raising the anodes to higher temperatures without introducing the danger of damaging the tube. 70 75

Of course it is to be understood that my invention is not limited to the particular details 75

of construction as set forth above inasmuch as many equivalents will suggest themselves to those skilled in the art. The invention sets forth certain broad principles which when utilized accomplish the novel results which I have described. It is accordingly desired, therefore, that the appended claims be given a broad interpretation commensurate with the scope of the invention within this art.

10 What is claimed is:

1. An electrical space discharge device comprising a sealed envelope containing a plurality of electrodes, one of said electrodes being heated to a relatively high temperature during opera-

15 tion, lead-in conductors for said electrodes sealed through the wall of said envelope, and an electrical connector made of a material of a lower order of thermal conductivity than the material of said heated electrode interposed between and electrically connecting said heated electrode and its associated lead-in conductor, said connector having a lower order of thermal conductivity than said heated electrode.

20 2. An electrical space discharge device comprising a sealed envelope containing an anode and a thermionic cathode, lead-in conductors for

25 said electrodes sealed through the wall of said envelope, and an electrical connector made of a material of a lower order of thermal conductivity than the material of said cathode interposed between and electrically connecting said cathode and its associated lead-in conductor, said connector as a whole having a lower order of thermal conductivity than said cathode.

30 3. An electrical space discharge device comprising a sealed envelope containing an anode and a thermionic cathode comprising a cathode sleeve coated with emitting oxide and a filamentary heater within said sleeve, lead-in conductors for said electrodes sealed through the wall of said envelope, and an electrical connector made of a material of a lower order of thermal conductivity than the material of said cathode sleeve interposed between and electrically connecting

35 said cathode sleeve and its associated lead-in conductor, said connector as a whole having a lower order of thermal conductivity than said cathode.

40 4. An electrical space discharge device comprising a sealed envelope having a glass wall containing a plurality of electrodes, one of said electrodes having a relatively high heat capacity and being heated to a relatively high temperature during operation, lead-in conductors for said electrodes sealed through said glass wall, and an electrical connector made of a material of a lower order of thermal conductivity than the material of said heated electrode interposed between and electrically connecting said heated electrode

and its associated lead-in conductor, said connector as a whole having a lower order of thermal conductivity than said heated electrode.

5. An electrical space discharge device comprising a sealed envelope containing a plurality of electrodes, one of said electrodes being heated to a relatively high temperature during operation, lead-in conductors for said electrodes sealed through the wall of said envelope, and an electrical connector consisting of an alloy of nickel and iron, having a lower order of thermal conductivity than the material of said heated electrode, interposed between and electrically connecting said heated electrode and its associated lead-in conductor, said connector having a lower order of thermal conductivity than said heated electrode.

6. An electrical space discharge device comprising a sealed envelope containing a plurality of electrodes, one of said electrodes being heated to a relatively high temperature during operation, lead-in conductors for said electrodes sealed through the wall of said envelope, and an electrical connector consisting of an alloy of nickel, containing more iron than nickel, and having a lower order of thermal conductivity than the material of said heated electrode interposed between and electrically connecting said heated electrode and its associated lead-in conductor, said connector having a lower order of thermal conductivity than said heated electrode.

7. An electrical space discharge device comprising a sealed envelope containing a plurality of electrodes, one of said electrodes being heated to a relatively high temperature during operation, lead-in conductors for said electrodes sealed through the wall of said envelope, and an electrical connector consisting of an alloy composed substantially solely of nickel and silicon interposed between and electrically connecting said heated electrode and its associated lead-in conductor, said connector having a lower order of thermal conductivity than said heated electrode.

8. An electrical space discharge device comprising a sealed envelope containing a plurality of electrodes, one of said electrodes being heated to a relatively high temperature during operation, lead-in conductors for said electrodes sealed through the wall of said envelope, and an electrical connector consisting of an alloy composed substantially solely of nickel and a small percentage of silicon interposed between and electrically connecting said heated electrode and its associated lead-in conductor, said connector having a lower order of thermal conductivity than said heated electrode.
